UNITED STATES PATENT OFFICE.

MICHAEL THOMAS REEHL, OF CINCINNATI, OHIO.

PELT-COMBING MACHINE.

989,419.

Specification of Letters Patent. Patented Apr. 11, 1911.

Application filed June 10, 1910. Serial No. 566,181.

To all whom it may concern:

Be it known that I, MICHAEL T. REEHL, a citizen of the United States, and a resident of Cincinnati, Hamilton county, State of Ohio, have invented a certain new and useful Pelt-Combing Machine; and I do declare the following to be a clear, full, and exact description thereof, attention being called to the drawing which accompanies this application and forms a part thereof.

This invention concerns a machine for combing the hair on animal pelts, the principal object being to remove impurities, foreign substances and hair which has lost its connection with the hide, also to straighten out the hair more or less, if matted.

A particular use for which this machine is well adapted is in connection with the combing of tanned, long wool and short wool sheep-skins, also shearlings, lambskins, etc.

The invention consists of a machine constructed as hereinafter described and claimed and as illustrated in the accompanying drawing, in which:

25 Figure 1, is a side-view of the machine, partly in section. Fig. 2, is a front-view of the same. Fig. 3, is a section on line 3—3 of Fig. 1, note this line also in Fig. 2. Fig. 4, is an enlarged sectional detail-view of a part of the combing wheel. Fig. 5, illustrates a detail of the comb. Fig. 6, is an enlarged vertical cross-section of a device operating in conjunction with the combing-wheel.

35 The hair or wool-covered hide is acted upon by a comb consisting of an endless surface studded with teeth which may be all of the same length or of different lengths. As shown, I use longer and stronger teeth 10 and shorter ones 11, both arranged in alternate groups. A preferable form of endless surface may be had by using rim 12 of a suitable wheel 13, mounted upon a power-actuated shaft 14. Power is shown as being applied in form of a pulley 15 alongside of which a loose pulley 16 is mounted.

45 The comb-teeth may be connected in any suitable manner, a preferable way being by means of sectional plates 17, fitted to the rim of the wheel and perforated to receive the teeth which are inserted from the inner side of these plates. The teeth are prevented from passing out of these plates by means of heads 18 as shown in Fig. 4, or they may be 50 formed as shown in Fig. 5, there being two teeth made out of one piece of metal, the

intermediate part 19 of the metal which connects the two teeth, holding them also in position on plate 17. After the teeth are placed on plates 17, these latter are connected to rim 12 of the wheel by bolts 21, whereby the teeth are firmly held in position at their inner ends, where they are clamped between plates 17 and rim 12 of the wheel.

55 22 is a table on which the combing-wheel 65 is supported in a manner that part of its periphery revolves above the upper surface of the table.

The operator stands opposite the face of the combing-wheel, it being to the left as 70 the same is shown in Fig. 1 which constitutes the front of the machine and the wheel revolves in a direction so that the teeth move away from the operator as shown by the arrow.

75 On the rear-side of the machine the table declines as shown at 23 and is formed by a multiperforated surface preferably in form of a screen 24.

80 The combing manipulation consists substantially of throwing the hide or skin upon the table, hairy side down and over the combing-wheel, the operator, without releasing his hold upon the skin, permitting at the same time the wheel to draw the same 85 toward the rear, after which he pulls it again toward him and against the movement of the combing-teeth, permitting it immediately to pass again to the rear. This action is repeated as often as necessary, the 90 position of the skin being constantly changed until all parts of the hair on it are subjected to the action of the combing-teeth. The screen over which the skin passes back and forth during this operation permits all 95 matter loosened by the combing-teeth to readily clear the hair and drop away therefrom. To prevent such matter from flying about promiscuously, I provide a gutter or channel 25 below the screen whereby this 100 refuse may be properly controlled and directed to move away from the machine.

105 26 is a guard to protect the hands of the operator by limiting approach to the combing-wheel.

Pressure should be applied against the upper side of the skin, sufficient to hold the same down against the combing-teeth to cause them to act properly and to prevent them from repelling the skin. I prefer to 110 use a roll 27 for such purpose, loosely mounted above the combing-wheel, so that

it may follow the movement of the skin without frictionally retarding the same. It is also yieldingly supported so that it may adjust itself to the thickness of the pelt and 5 give way if a thicker portion of the same passes under it. Furthermore its surface which contacts with the skin is soft to prevent injury to this latter. This softness is obtained by the use of a pelt-covering 28 10 which may be made of wool-covered sheep-skin stretched around the center of the roller, which center may be wood. This covering may be stretched directly around this center, or padding material 29, which 15 may be wool, may be interposed. This roll is supported in bearings formed at the lower end of two rods 31, provided with heads 32 at their upper ends whereby they are hung on a cross-bar 33. This support is one which 20 permits these rods to move vertically and they are held to such a movement by suitable guiding-means as for instance by cross-timbers 34 and 35 which form parts of a general frame and through which timbers 25 these rods loosely pass. The position of cross-bar 33 on which these rods 31 loosely hang, being held there by their heads 32, controls the lowermost position of roll 27 with reference to the combing-wheel. This 30 lowest position may be adjusted by means of a bracket 36 on bar 33, held on the upper frame-timber 35 by a pin 37. When this pin is removed, the entire suspended structure may be conveniently raised or lowered 35 by means of a lever 38 and pull chain 39. The weight of this suspended structure and added weights if necessary may be relied upon to hold it to its normal lowest position and to return it to this position if perchance 40 a thicker pelt has temporarily raised it. This action may be augmented by spiral springs 41 sleeved upon rods 31 and confined between shoulders 42 on them and the upper frame-timber 35. 45 It will be noted that the combing-teeth

are secured to the wheel-rim in a position inclined to this latter and more particularly in a direction inclining opposite to that in which the wheel revolves, so as to prevent hair from being torn from the skin, more particularly in the case of wool-covered sheep-skin. 50

Having described my invention, I claim as new:

1. In a pelt-combing-machine, the combination of a table, a toothed combing-wheel supported so that part of it revolves above the table and a pressure-device yieldingly supported above the combing-wheel with a space between the two. 55

2. In a pelt-combing-machine, the combination of a combing-wheel and a pressure-roll having a hair-covered face supported opposite the former with a space between the two. 60

3. In a pelt-combing-machine, the combination of a table, a toothed combing-wheel supported so that part of it revolves above the table, and a guard on this latter and in front of the face of the wheel. 65

4. In a pelt-combing-machine, the combination of a table, a toothed combing-wheel supported so that part of it revolves above the table and a screen provided in an inclined position back of the combing-wheel. 70

5. In a pelt-combing-machine, the combination of a table, a toothed combing-wheel supported so that part of it revolves above the table, a pressure-roll supported above this combing-wheel in a fixed, lowermost 80 position with a space between the two and free to yield upwardly and means to adjust the fixed lowermost position of the roll.

In testimony whereof, I hereunto affix my signature in the presence of two witnesses. 85

MICHAEL THOMAS REEHL.
